WITNESS:

UNITED STATES PATENT OFFICE.

THOMAS O. MOUNTAIN, OF EL PASO, TEXAS.

VALVE.

Application filed February 21, 1922. Serial No. 538,273.

To all whom it may concern:

Be it known that I, THOMAS O. MOUNTAIN, a citizen of the United States, residing at El Paso, in the county of El Paso and State of Texas, have invented new and useful Improvements in Valves, of which the following is a specification.

The object of this invention is to provide means for preventing a tank or container from overflowing, when being filled through a hose or the like.

Another object of the invention is to make such means automatic so that as soon as the liquid reaches a point adjacent the top of the tank the flow of liquid through the hose or other filling medium will be stopped.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is an elevation of the invention. Figure 2 is a longitudinal sectional view thereof showing the parts thereof in inoperative position.

Figure 3 is a similar view showing the parts in operative position.

Figure 4 is a view showing the invention applied to a gasoline delivery pump.

Figure 5 is a view showing the invention applied to another kind of pump.

The remaining figures are detail views.

In these views 1 indicates a faucet which is adapted to be connected with a hose 2 or the like which delivers the liquid from the source of supply to the passage 3 of the faucet. A valve 5 controls the flow of liquid through this passage, said valve being adapted to engage a seat 6, which separates one part of the passage from another part, when the valve is in closed position and said valve is adapted to engage a recess 7 when in open position, said recess being below the level of the passage so that the valve will not interfere with the flow of liquid. I may make the bottom of this recess removable, as shown at 8, so as to facilitate assembling of the parts. A cylinder 9

is formed in the faucet above the passage 3 therein and the valve stem 10 passes through this cylinder, suitable packing means, such as shown at 11, being arranged on the bottom of the cylinder to prevent leakage of the liquid from the passage into the cylinder. A piston 12 is located in the cylinder and this piston is secured to the valve stem, as shown. The valve stem passes through a hole in the top of the cylinder and the lower end of the cylinder is provided with an opening 13 which communicates with the atmosphere. A jacket 14 is formed around the outlet portion of the faucet and the space formed by this jacket is in communication with the cylinder through the port 15. A passage 16 has one end connected with the upper end of the cylinder and its other end is adapted to be connected to a pipe or tube 17 which leads to a suction creating part 75 hereinafter referred to.

The drawings show the invention applied to gasoline delivering pumps of the two different types, though it will of course be understood that the invention can be used in filling containers of all kinds.

Referring to Figure 4 the outlet of the pump 18 is connected by the hose 19 with my improved faucet so that the gasoline flowing from the pumps will pass through the hose into the faucet and from the faucet into the tank of the motor vehicle. The piston of the pump 18 is provided with the usual rack 20 which is engaged by the toothed wheel 21 connected with the handle 22. A small cylinder 23 is supported by the pump and the piston 24 of the cylinder is connected with the rack so that the piston will move when the pump is being actuated. The bottom of the cylinder 23 is connected by the tube 17' with the passage 16 so that as the pump is actuated air will be drawn through the jacket space, into cylinder 9, through passage 16 and tubing 17' into the lower part of the cylinder 23. As the valve 5 is in open position the piston 12 will be below the port 15 and will not interfere with the passage of the air through the cylinder. When the liquid in the tank or other container being filled reaches a level where it will close the end of the jacket space the flow of air through this space into the cylinder will be shut off so that a vacuum will take place in the cylinder and this will lift piston 12 above the port 15 and move the 110

valve 5 upon its seat thus stopping the flow of liquid through the faucet. The resulting back pressure in the pump holes will prevent further movement of the pump parts 5 so that the operator will know that the tank is full and thus prevent overflowing of the tank. The hose and faucet can be drained by pushing downwardly upon the valve stem, which projects above the top of the 10 cylinder, so as to force the valve from its seat.

Figure 5 shows the device applied to a visible form of pump in which a "bottle" 25 is used to receive the liquid pumped out 15 of the supply tank. After the proper amount of liquid has been pumped into the bottle a valve 26 is opened to permit the liquid in the bottle to flow through the holes into the tank of the vehicle. In this case I connect 20 the tubing 17" with the top of the bottle so that the flow of liquid therefrom will create a suction in the cylinder and as soon as the flow of air is cut off by the liquid reaching the end of the jacket space this suction will 25 cause the piston in cylinder 9 to raise thus closing the valve 5 and preventing the liquid from passing into the tank. The operator must then close valve 26.

It will thus be seen that the device will 30 work automatically to prevent overflowing of tanks or other containers. Any suitable form of suction means may be connected with the cylinder for moving the valve to closed position when the tank or container 35 is filled.

It is thought from the foregoing description that the advantages and novel features of my invention will be readily apparent.

I desire it to be understood that I may

make changes in the construction and in the 40 combination and arrangement of the several parts, provided that such changes fall within the scope of the appended claims.

What I claim is:—

1. A faucet of the class described comprising a normally opened valve, a suction chamber connected with the faucet and through which the valve stem passes, a piston in said chamber connected with the stem, a connection from the chamber to a 50 point adjacent the outlet end of the faucet and means for drawing air from the chamber.

2. A device of the class described comprising a body having a passage therethrough, means for connecting one end of said passage to a source of liquid supply, a valve for controlling said passage, a cylinder forming part of the body and through which the valve stem passes, a piston in the 60 cylinder connected to the valve stem, a passage leading from said cylinder to a point adjacent the outlet end of the passage and means for drawing air from the upper end of the cylinder.

3. In combination with a gasoline pump, a faucet connected with the hose thereof, a normally opened valve in the faucet, a cylinder forming part of the faucet and through which the valve stem passes, a piston in the cylinder connected with the stem, a passage leading from the lower part of the cylinder to a point adjacent the outlet end of the faucet and means associated with the pump for drawing air from the top of the 75 cylinder.

In testimony whereof I affix my signature.
THOMAS O. MOUNTAIN.
